LIFTING CLAMP

Eugene McGowan, New York, N. Y.

Application August 11, 1945, Serial No. 610,385

1 Claim. (Cl. 294—104)

(Granted under the act of March 3, 1883, as
amended April 30, 1928; 370 O. G. 757)

1

This invention relates to a lifting clamp and more particularly to a lifting clamp for use in handling I beams, T beams and the like.

An object of this invention is to provide a clamp for lifting I beams, T beams and similar structural members without danger of slippage.

Further objects and advantages of this invention, as well as its construction, arrangement and operation, will be apparent from the following description and claim in connection with the accompanying drawing, in which,

Fig. 1 is an isometric view of a preferred form of the present invention,

Fig. 2 is a side elevational view of the device shown in Fig. 1 being used on a T beam, and

Fig. 3 is a sectional view taken on line 3—3 of Fig. 2.

The lifting clamp 11 has an integrally formed body portion 12 provided with horizontal supporting arms 13 and 14, and a bifurcated vertical fork 15.

Fork 15 has parallel projections 16 and 17 provided with transverse coaxial bores 18 and 19. Pin 20 extends through bores 18 and 19, and rotatably supports lever 21 adjacent the middle portion thereof. At one end of lever 21 is located the jaw 22 having teeth 23 and at the opposite end bore 24 which is adapted to be connected to a supporting cable.

In using the clamp to pick up one end of a T beam 25 as shown in Figs. 2 and 3 the supporting

2

arms 13 and 14 are slipped under the horizontal flanges 26 and 27 and on either side of vertical web 28. Another similar clamp is preferably positioned at the opposite end of the T beam and a cable secured to the bores 24 on both clamps. The upward tension on the bore 24 resulting from hoisting forces the jaw 22 against the upper surface of the T beam and securely clamps the beam against the arms 13 and 14. The teeth 23 prevent the device from slipping off while an upward pressure is exerted at bore 24, but when the pressure is released the device is readily disengaged.

It is to be understood that various modifications and changes may be made in this invention without departing from the spirit and scope thereof as set forth in the appended claim.

The invention described herein may be manufactured and used by or for the Government of the United States of America for governmental purposes without the payment of any royalties thereon or therefor.

What is claimed is:

A lifting clamp comprising a body portion, a pair of horizontally extending, laterally spaced arms on said body, a fork extending upwardly from said body, a bore through said fork, a rod mounted in said bore, a lever pivotally mounted on said rod, a bore at one end of said lever and a jaw at the opposite end of said lever adapted to be positioned in clamping relation with said arms.

EUGENE McGOWAN.
